UNITED STATES PATENT OFFICE

2,636,490

HOT OIL HEATER AND CIRCULATOR

William J. Miller, Youngstown, Ohio

Application November 14, 1950, Serial No. 195,564

7 Claims. (Cl. 126—343.5)

1

This invention relates to hot oil heaters and circulators for use with asphalt storage tanks, tank cars, etc., and any and all applications wherein asphaltic or bituminous materials must be heated to maintain the same in fluid condition for handling purposes.

The principal object of the invention is the provision of a hot oil heater and circulator for the efficient heating and handling of a fluid heating medium.

A further object of the invention is the provision of a hot oil heater incorporating novel heat exchange means.

A still further object of the invention is the provision of a hot oil heater and circulating device including interconnected storage, heating and surge tank portions for a fluid heating medium and circulating means for moving the fluid heating medium therebetween.

A still further object of the invention is the provision of a hot oil heater and circulating device including means for circulating a fluid heating medium from a heating portion of the device to and from an object to be heated.

It is known in the art that various storage tanks, transportation tank cars and the like for asphaltic and bituminous materials are commonly supplied with heat exchangers through which it has been customary to circulate steam from a permanent or portable steam boiler installation and for the purpose of maintaining the asphaltic or bituminous materials in fluid or semi-fluid condition.

The present invention relates to a specific form of hot oil heater and circulating device which can be used primarily as a portable heating unit for supplying heat to storage and/or transportation tanks of asphaltic or bituminous materials such as commonly used in connection with road paving jobs and particularly asphaltic concrete constructions. The hot oil heater and circulator disclosed herein is constructed as a compact, relatively small unit entirely self-sufficient in that it includes storage space for the fluid heating medium, means for heating the liquid heating medium, a surge tank so arranged as to be usable as storage space for the fluid heating medium and pumping means whereby the liquid heating medium (usually a suitable oil) may be supplied the heating unit, heated to the desired temperature, for example, 350° F., circulated from the device to the object to be heated, returned to the device and reheated. The device is also arranged so that the liquid heating medium can be pumped into the de-

2

vice from an outside point; pumped from the storage portion of the device to the surge tank to increase storage capacity; pumped from the heating unit of the device to the surge tank thereof; pumped from the work served and the connecting lines so as to empty the same; and pumped from the supply tank to the surge tank of the device under automatic control to maintain a desired level.

With the foregoing and other objects in view which will appear as the description proceeds, the invention resides in the combination and arrangement of parts and in the details of construction hereinafter described and claimed, it being the intention to cover all changes and modifications of the example of the invention herein chosen for purposes of the disclosure, which do not constitute departures from the spirit and scope of the invention.

The invention is illustrated in the accompanying drawing, wherein:

Figure 1 is a side view of the hot oil heater and circulator.

Figure 2 is an end view of the hot oil heater and circulator.

Figure 3 is a vertical section taken on line 3—3 of Figure 2.

Figure 4 is a schematic diagram incorporating interconnecting fluid flow lines.

Figure 5 is a wiring diagram.

By referring to the drawings and Figures 1 and 2 in particular it will be seen that the hot oil heater and circulator comprises a storage tank 10 forming a base having the upper portion thereof formed in a transverse arc or concave surface whereby a longitudinal channel is formed for the reception and positioning of a cross sectionally circular heating unit 11. The upper portion of the storage tank 10 thereby partially encircles the heating unit 11 as the heating unit 11 is, in effect, nested in the upper portion of the storage tank and approximately one-third of its area is in engagement with the storage tank. The heating unit 11 supports a horizontally positioned flat surge tank 12 positioned directly above the heating unit and closely spaced with respect thereto so as to form a radiant and thermal heat baffle with respect to the upper surface of the heating unit 11 and thereby increase the operating efficiency thereof. Several intercommunicating pipes are arranged between the storage tank 10, the heating unit 11 and the surge tank 12 as will be hereinafter more fully described.

A projecting end section 13 of the tank 10 forms

a platform supporting a main circulating pump 14, a motor 15 coupled thereto and a secondary circulating pump 16 having a motor 17 coupled thereto for driving the same. The main circulating pump 14 has its inlet 18 in communication with a pipe 19 which in turn communicates with the uppermost portion of the heating unit 11 and an outlet 20 which is adapted to be connected to the work to be heated such as a heat exchanger in a tank of asphaltic material. The heating unit 11 has a pipe 21 in connection therewith through which the liquid heating medium circulated by the pump 14 is returned to the hot oil heater. By referring to Figures 1 and 3 of the drawings it will be observed that this pipe 21 communicates with the lowermost portion of the heating unit 11.

By referring to Figure 3 of the drawings it will be seen that the heating unit 11 comprises a double walled tank, the inner wall of which is indicated by the numeral 22 and forms a horizontally disposed tubular passageway from one end of the heating unit 11 to the other. The chamber formed between the outer wall of the heating unit 11 and the inner wall 22 is indicated by the numeral 23 and will thus be seen to completely surround a combustion chamber 24 which is defined by the inner wall 22.

A fuel burner 25 is positioned at one end of the device and discharges fuel through a nozzle 26 into the chamber 24. The nozzle 26 is positioned through an end closure 27 which is double walled and insulated and the whole of which is removably mounted on the heating unit 11 as by studs 28 which are affixed thereto. A stack 29 is located at the opposite end of the device and extends vertically through the liquid chamber 23 and establishes communication between the combustion chamber 24 and the atmosphere.

A pair of spaced valved pipes 30 establish communication between the surge tank 12 and the chamber 23 and also serve as legs supporting the flat surge tank 12 in its position immediately above the heating unit 11. A third supporting pipe 31 is also provided for positioning and supporting the surge tank 12 and it is in communication with the liquid chamber 23 of the heating unit 11 and with the surge tank 12. By referring to Figure 3 of the drawings pipe 31 will be seen to extend upwardly in the surge tank 12 to a point even with the uppermost wall thereof and immediately within a dome 32.

A pair of circular apertured baffles 33—33 are positioned on a movable support 34 in the combustion chamber 24 and are adapted to be moved longitudinally thereof so that products of combustion introduced into the combustion chamber 24 through the nozzle 26 will be directed by the baffles for suitable impingement with the inner wall 22 to facilitate the heat transfer into the liquid heating medium in the chamber 23.

By referring again to Figures 1 and 2 of the drawings it will be seen that a pipe 35 communicates with the storage tank 10 and with the surge tank 12 and extends upwardly thereinto to a point near the upper wall thereof. A pipe 36 connects the surge tank 12 with a four-way valve 37 controlling the output of the secondary pump 16 heretofore referred to and a pipe 38 connects the four-way valve 37 with the pipe 19 at a point adjacent the inlet 18 heretofore referred to and between the said inlet 18 and a valve 39 controlling the pipe 19. Another pipe 40 extends from the four-way valve 37 to the pipe 21, heretofore mentioned, as forming the inlet to

the heating unit 11 and as best illustrated in the schematic view comprising Figure 4 of the drawings.

A fourth pipe 41 extends from the four-way valve 37 to the storage tank 10 so that the liquid medium employed may be moved from one portion of the device to another by the secondary pump 16. For example, when it is desired to initially fill the device with a suitable liquid medium, a valve 42 in the pipe 38 is closed and a valve 43 controlling a T 44 communicating with the piping 38 adjacent the valve 37 is opened, the valve 43 being in communication with a source of suitable liquid. Operation of the secondary pump 16 will then pump liquid from the supply source (not shown) through the valve 43, the T 44, the pipe 38, the four-way valve 37 and into the storage tank 10 by way of the pipe 41.

When the storage tank 10 is filled, the liquid medium will then flow upwardly through the pipe 35 into the surge tank 12 and from there through the connecting pipes 36, assuming that the valves normally controlling these lines are open. Thus the entire fluid capacity of the device may be utilized, for example, in transporting the same to an indicated location and thereby enabling it to carry along the necessary amount of the liquid heating medium.

Upon changing the setting of the four-way valve 37 when the device is in operation and in communication with a heat exchanger (not illustrated), the secondary pump 16 operates to move liquid from the storage tank 10 by way of the pipes 41 and 36 to the surge tank 12 where it is in normal communication with the heating unit 11 and may thus be used to replenish the liquid medium required to fill the connecting piping and the heat exchanger.

It will thus be seen that when the device is in operation and the main circulating pump 14 operating, the liquid heating medium will be continually withdrawn from the top of the heating unit 11, circulated through the heat exchanger and returned to the heating unit through the pipe 21. In the event of loss of liquid heating medium in the connecting piping or heat exchanger, the heretofore described action of the secondary pump 16 will withdraw liquid from the storage supply tank 10 and replenish the liquid in the actual heating system circuit. Means for controlling this operation automatically is provided and comprises a double acting control device 45, the same being actuated by a float 46 in the surge tank 12 so that upon the lowering of the level of the liquid medium in the surge tank 12 the secondary pump 16 will be automatically actuated to replenish the same as heretofore described and simultaneously the burner 25 will be shut down until such time as the liquid level in the surge tank is again normal at which time the control 45 will stop the secondary pump 16 and re-energize the burner 25.

The secondary pump 16 is also used at the time the device is disconnected from the heat exchanger as it may then be employed for withdrawing the liquid medium from the heat exchanger and connecting piping by way of the pipe 38 discharging the same through the pipes 41 or 36 into the device so that the complete liquid medium may again be retained by the device and no additional storage tanks are necessary. This operation is accomplished by closing the valve 39 in the pipe 19, opening the valve 42 in the pipe 38 and closing the valve 43 and setting the four-way valve 37 so that action of the secondary pump

16 moves liquid from the pump 14 and the connecting piping into the storage tank 10 and/or surge tank 12 of the device which may then again be completely refilled and the same utilized as storage capacity. Alternately the liquid heating medium may be pumped from the device and its connected lines to a remote storage tank by way of the T 44 and valve 43.

It will thus be seen that the hot oil heater and circulator comprises a completely self-contained unit capable of supplying itself with liquid heating medium, moving the same from storage to heating portions thereof as needed, and that it also includes an efficient heating unit and circulating means for heating the liquid heating medium used and circulating the same through a heat exchanger in an area to be heated. The efficiency of the heating portion of the device is enhanced by its design and arrangement and particularly with respect to the partial envelopment of the heating unit 11 by the storage tank 10 and the surge tank 12. The movable baffles 33-33 enable the flame from the burner to be impinged on the inner wall 22 of the unit 11 so as to result in a rapid heat transference to the liquid medium in the chamber 23.

It will be observed that the return flow of the circulating liquid medium is into the lowermost portion of the heating unit 11 and that the withdrawal of the heated liquid medium is from the highest point thereof. This insures continuous circulation of the liquid heating medium through the device and about the inner wall 22 thereof. The orifices in the baffles 33 contribute to the over all efficiency of heat transfer of the device and furthermore permit visual control of the burner 25 through a peephole formed in a closure affixed to the opposite end of the unit with respect to the burner 25.

It will be observed that the burner 25 is supported on the end closure 27 and in completely elevated relation to the driving motors 15 and 17 and the main and secondary pumps 14 and 16 to provide ready access thereto. The device is also provided with a temperature limiting control 48 electrically connected in the circuits controlling the burner 25 so that upon the liquid heating medium reaching a predetermined temperature the burner is automatically shut down. The burner 25 is of a type known in the art and includes a motor driven fuel oil pump, carburetor and blower for processing the fuel before delivering the same to the nozzle 26 and the combustion chamber 24 as heretofore described.

The entire device is of compact construction and occupies relatively small space and is therefore adapted to be mounted on a trailer, thus rendering the same portable. The control 48 is also arranged to operate the burner 25 to maintain desirable operating temperatures at between 300° F. and 375° F. in the chamber 23.

It will thus be seen that the hot oil heater and circulator disclosed herein meets the several objects of the invention.

Having thus described my invention, what I claim is:

1. In a hot oil heating and circulating device the combination of a storage tank, a heating unit and a surge tank positioned above and supported by the heating unit, the storage tank and surge tank partially covering the lower and upper portions of said heating unit, a combustion chamber in said heating unit, a principal circulating pump, tubular connections between said heating unit and said principal circulating pump and together therewith constituting means for circulating a

liquid medium from said heating unit to a place of use and return to the heating unit through said tubular connections, secondary tubular connections establishing communication between the storage tank and the heating unit and the surge tank and a secondary pump for moving the liquid medium therethrough, a valve in said secondary tubular connections, said valve comprising a four-way valve interconnecting said secondary tubular connections and said secondary pump, and flow control valves in said secondary tubular connections between said secondary pump and said heating unit, a third set of tubular connections between said surge tank and said heating unit and burner means for introducing and maintaining a combustible mixture in the said combustion chamber of said heating unit.

2. The apparatus set forth in claim 1 and further characterized by control means on said surge tank responsive to the liquid level therein, said secondary pump being responsive to said control means in moving liquid from said storage tank to said surge tank.

3. The apparatus set forth in claim 1 including control means in said surge tank for said burner means and the secondary pump, said burner means being responsive in operation to said control means and said pump being responsive in operation to said control means whereby liquid from said storage tank may be moved to said surge tank and whereby the said burner means is responsive to the liquid level in said surge tank.

4. A hot oil heater and circulating device including a double walled heating unit defining a longitudinal combustion chamber and an annular liquid chamber, means for introducing and maintaining a combustible mixture in said combustion chamber, a surge tank positioned over said heating unit and acting as a thermal baffle with respect thereto, means establishing communication between said surge tank and said liquid chamber, the liquid chamber being provided with inlet and outlet orifices, a principal circulating pump, a tubular connection between said principal circulating pump and said outlet orifice whereby liquid heating medium may be circulated through the device and a place of use, a storage tank supporting said heating unit and partially enveloping the same, a secondary pump, communicating means connecting the said storage tank and the said surge tank whereby liquid heating medium in the said heating unit and surge tank may be maintained by pumping from the said storage tank, and control means in said surge tank responsive to the liquid level therein for controlling said secondary pump.

5. A hot oil heater and circulating device comprising a storage tank having a longitudinally extending transversely arcuate concaved top portion, a cylindrical heating unit positioned on said storage tank and resting in the concave top portion thereof so as to be partially enveloped by the said top portion of the said storage tank, said heating unit having a tubular core disposed longitudinally therein in spaced relation to walls of the heating unit and defining a combustion chamber within the same, the space between the said tubular core and the walls of the cylindrical heating unit being closed at its ends and forming a liquid heating chamber, a stack in communication with said combustion chamber at one end of the device, a fuel burner in communication with the combustion cham-

ber at the other end of the device, a surge tank in communication with said liquid heating chamber and positioned immediately above the said heating unit, said surge tank having a horizontally flat bottom acting as a radiant and thermal baffle with respect to the cylindrical heating unit, and means establishing communication between the surge tank and the storage tank including conduits and a pump for transferring a liquid heating medium from one portion of the device to another whereby a desirable liquid level may be maintained in the liquid heating chamber and the surge tank.

6. The hot oil heater and circulating device as set forth in claim 5 including a liquid level responsive control in said surge tank, the said pump being responsive in operation to the said liquid level responsive control.

7. The hot oil heater and circulating device as set forth in claim 5 wherein the cylindrical heating unit is formed with inlet and outlet orifices communicating with the liquid chamber,

and a circulating pump in communication with one of said orifices whereby liquid in the said liquid heating chamber may be delivered to a place of use and returned through the other one of said orifices.

WILLIAM J. MILLER.
